UNITED STATES PATENT OFFICE.

GEORGE SWEET, OF OAKLAND, CALIFORNIA.

WATER-HEATER.

1,277,664.

Specification of Letters Patent.

Patented Sept. 3, 1918.

Application filed February 12, 1917. Serial No. 147,972.

To all whom it may concern:
Be it known that I, GEORGE SWEET, a citizen of the United States, residing at Oakland, county of Alameda, State of California, have invented certain new and useful Improvements in Water-Heaters; and I do declare the following to be a full, clear, and exact description of the same, reference being had to the accompanying drawings, and 10 to the characters of reference marked thereon, which form a part of this application.

This invention relates to improvements in water heaters, the object of the invention being to produce a heater having an extensive heating area together with a means combined therewith for rapidly heating a thin film of the water passing through the heater just as soon as the heating element is in operation so that there can be an immediate withdrawal of the heated water from such heater.

A further object of the invention is to produce a simple and inexpensive device and yet one which will be exceedingly effective for the purposes for which it is designed.

These objects I accomplish by means of such structure and relative arrangement of parts as will fully appear by a perusal of 30 the following specification and claim.

In the drawings similar characters of reference indicate corresponding parts in the several views.

Figure 1 is a front elevation of the complete heater showing the door partly ajar.

Fig. 2 is a fragmentary portion of the upper end of the inner tube.

Fig. 3 is a similar view of the lower end.

Fig. 4 is a top plan view of the heating 40 unit.

Fig. 5 is a vertical sectional view of the complete heater.

Referring now more particularly to the characters of reference on the drawings the 45 numeral 1 designates the casing of the heater which may be of any desired type having a plurality of inlet openings 2 around the lower end where the heating unit will be disposed, and an outlet flue 3 at the upper end.

The water is conveyed to the heating area through the pipe 4 which extends vertically through the bottom of the casing 1 to a point immediately above the heating unit. 55 At such point it is provided with a pair of projecting lateral pipes 5 and 6, one of

which connects with a coil 7 and the other connects with a coil 8, the coil 7 being spaced within the coil 8. The pipe 4 extends upwardly from the branches 5 and 6 and connects with a main cylindrical tube 9, of a larger diameter than the said pipe 4, such tube 9 reducing in size at its lower end 10 for connection with the said pipe 4. At this point of reduction an inner tube 11 is projected into the tube 9 and is of a slightly lesser diameter than the tube 9 forming an intervening space 12. Both ends of this tube 9 are pressed in the manner illustrated in Fig. 2, closing it completely, and forcing the water passing through the pipe 4 to divide and run through the space 12. The upper end of the tube 9 is constructed similarly to the lower end, that is, it reduces as at 10^a, to 60 connect with another pipe 4^a of the same diameter as the pipe 4. In making this structure the tube 11 is projected in the tube 9 and the reduced ends 10 and 10^a are 65 then brazed onto the tube 9 after having been fitted firmly against the tube 11. This is the preferable form of construction although of course, other desired methods might be employed. The pipe 4^a has a pair of branches 5^a and 6^a which receive the 70 terminals of the coils 7 and 8 respectively. The pipe 4^a projects through the top of the casing 1 and is provided with two lock nuts 13 and 14, one on each side of the top 75 of the casing whereby the heating area is suspended in desired position within the casing 1. The heating unit comprises two annular passage ways 15 and 16, spaced one within the other and connected by radial passage ways 17. These passage ways are of 80 a considerable depth as shown and provided with burner outlets 18. Two inlet pipes 19 communicate with the passage way 15 for the admission of gas. The depth of the passage ways 15 and 16 allows of a pre-heating 85 and expansion of the gas prior to its passing out through the openings 18 so that when combustion takes place I attain the greatest degree of heat units possible, which of course greatly increases the efficiency of 90 the heater.

The burning gas passes up through the coils 7 and 8 and around the tube 9. There is a film of water passing through the space 12 and this tends to heat very rapidly so that when the water is drawn from the heater when in operation it is but a very 95 100 105 110

short time before it is thoroughly heated. The spaced coils in combination with the vertical double tubing presents a great amount of heating area to the flame. In 5 addition to this, as each coil and each tube becomes thoroughly heated it tends to hold all the heat units in the casing 1 and not allow any waste thereof. The air for combustion purposes is admitted through the 10 openings 2.

From the foregoing description it will be apparent that I have a water heater having some very advantageous features for providing quick action on the film of water 15 in the chamber 12 together with a special construction for utilizing as many of the heat units as possible.

It will also appear from the above description that I have produced such a device as substantially fulfills the object of 20 the invention as set forth herein.

While this specification sets forth in detail the present and preferred construction

of the device, still in practice such deviations from such detail may be resorted to 25 as do not form a departure from the spirit of the invention as defined by the appended claim.

Having thus described my invention what I claim as new and useful and desire to 30 secure by Letters Patent is:

A water heater comprising a heating chamber, a pair of tubular members of different diameters arranged one within the other inside the heating chamber, the outer member being gradually reduced at its ends to form an inlet and an outlet for connection with water pipes, the inner member engaging and being held in position by the shoulders of the reducing portions of the 40 outer member and being pressed inwardly at its ends to close the same and form passageways from the outer member proper to the inlet and outlet thereof.

In testimony whereof I affix my signature. 45
GEORGE SWEET.
